UNITED STATES PATENT OFFICE

WILLIAM REX BELL, OF TERRE HAUTE, INDIANA

POSTER-SIGN-REMOVAL PROCESS

Application filed March 23, 1928. Serial No. 264,144.

This invention relates to a process of poster sign copy removal.

The chief object of the invention is to provide a construction which will permit the removal of paper copy from poster sign surfaces in a relatively short time and at a relatively low cost and the reapplication of the removal medium.

The chief feature of the invention consists in the accomplishment of the foregoing object by interposing between the sign surface adapted to receive the posting paper copy and the latter, a sheet of fabric material that is initially detachably secured to the sign receiving surface and to which the poster paper copy is subsequently secured so that removal of the fabric sheet material will simultaneously remove the poster paper copy whereupon, the removed poster paper copy and sheet material may be subsequently separated, and the fabric immediately reapplied to the sign receiving surface for additional copy reception.

The full nature of the invention will be more clearly understood from the accompanying drawings and the following description and claims.

In the drawings Fig. 1 is a perspective view of an outdoor or poster sign with the invention applied thereto and with a portion of it and the copy removed from the sign receiving surface. Fig. 2 is an enlarged perspective view of the sign receiving surface and the copy secured thereto, successive layers being successively cut away in sections to illustrate the invention.

In the drawings 10 indicates a conventional framework of an outdoor or poster sign supported as at 11 and 12 and including a copy receiving surface 13.

The foregoing is old in the art. Heretofore in the art of posting outdoor signs it has been necessary to remove from the sign receiving surface the copies that had accumulated thereon after three, or possibly four and usually never more than five, thicknesses of copy paper had been pasted upon the surface, if good service was desired.

To remove such accumulated copy material from a poster sign surface, heretofore

there was employed a sharp steel scraping instrument and the same was manually manipulated to cut, chop and scrape the surface to remove therefrom said accumulated paper copy. The removal of poster copy by this method usually, sooner or later, results in a marred sign receiving surface so that the marring becomes cumulative and soon excessive, for the marring will be increased at each subsequent cleaning in the endeavor to remove from previous mars the old copy that has accumulated therein.

At present prices, the labor cost of removing a unit of this copy material runs about \$2.75. With the present invention the initial cost for the same unit to prepare the same is \$1.50 and the cost of removing the copy does not exceed fifty cents, so that the total initial cost and subsequent removal for the first removal is materially less than the initial removal cost of the first removal under the old practice, and as will hereinafter be set forth, each subsequent removal of poster copy under the present process will only cost about fifty cents or less, the prices quoted being as of the present time but serving as an illustration of the comparative commercial value and saving obtainable by practicing the present process.

The process contemplates pasting upon the sign receiving surface 13, a sheet or matched sheets of fabric material 15 so that said sheet material completely covers the sign or copy receiving surface thereof. After this material has been applied to the sign receiving surface the copy 16 may then be pasted upon the fabric, which may be cheese cloth or any other suitable material and in the usual manner.

After the copy has been on the board the desired length of time, and usually this is about thirty days, the second sheet of copy material 17 may be applied to the first sheet in the same manner as at present applied and so on until the amount of paper on the panel is such that the irregularities in the previously applied paper copy forms such an irregular surface that subsequent poster copy cannot be applied thereto and secure good service. When the built up surface is of this character,

instead of using the scraping tool as heretofore practiced, one corner of the sheet material is worked loose from the board and the cloth or sheet material with the superposed copy, which has been secured to it, is stripped or pulled from the board. After the cloth or fabric and the copy have been removed from the board the same may be crumpled so as to break the adhesive connection between the fabric and the paper, whereupon the two may be readily separated and then the cloth or sheet material can be reapplied to the sign receiving surface as previously set forth.

It will be apparent from the foregoing that there is no marring of the sign receiving surface since there is no use of the scraper tool required. Also, whereas under the old practice of removing paper the time consumed was about two hours, the present invention only requires but a very few minutes. Furthermore, the present invention has the advantage that the cloth will adhere more closely and for a greater length of time to the steel face of the posting surface than the paper, and said cloth also will cover cracks, rust spots and such holes as may be found in the sheet metal thereby giving a better posting surface and, of course, longer life to the sign.

30 The invention, therefore, contemplates the practice of the process and the sign per se, as set forth in the appended claims.

The invention claimed is:

1. A paper posting process comprising detachably securing to a poster sign surface, prior to the posting of paper copy thereon, a fabric sheet material for covering the poster copy receiving surface, applying thereto at successive intervals of desired duration a plurality of successively positioned sheets of paper copy, stripping said fabric sheet from said sign receiving surface for simultaneously removing the superposed accumulated paper copy therefrom, separating the adhering paper copy from the sheet material when removed from the sign surface, and immediately re-applying the paper detached fabric sheet to the sign receiving surface for subsequent use upon the latter.

50 2. A paper posting process comprising detachably securing to a poster sign surface a fabric sheet material for covering the copy receiving surface, applying thereto at successive intervals of time sheets of paper copy, simultaneously stripping said fabric sheet with the superposed accumulated paper copy thereon from said sign receiving surface when a sufficient number of layers of copy have been applied thereto, separating the adhering paper copy from the sheet material by breaking the adhesive connection between the fabric and paper by crumpling the same, then separating all of the paper from the fabric, and then reapplying the paper detached fab-

ric sheet to the sign receiving surface for simultaneous paper copy reception.

In witness whereof, I have hereunto affixed my signature.

WILLIAM REX BELL.
